UNITED STATES PATENT OFFICE.

JEROME W. BARNARD, OF JOSEPH, OREGON, ASSIGNOR OF ONE-HALF TO ERNEST C. SKILES, OF JOSEPH, OREGON.

BOTTLE-BRACKET.

932,366.

Specification of Letters Patent. Patented Aug. 24, 1909.

Application filed December 19, 1908. Serial No. 468,384.

To all whom it may concern:

Be it known that I, JEROME W. BARNARD, a citizen of the United States, residing at Joseph, in the county of Wallowa and State of Oregon, have invented a new and useful Bot-
5 tle-Bracket, of which the following is a speci-
fication.

It is the object of the present invention to provide a novel construction of bracket for
10 supporting a bottle or similar container firmly in place upon a wall or the like but in such a manner that it may be readily re-
moved from the support.

The invention contemplates the provision
15 of a bracket of this type which is so con-
structed as to securely grip the bottle being supported, upon all sides, but to form the gripping members at the front of the device of less height than those at the sides so that
20 by grasping the neck of the bottle and swing-
ing or tilting the same forwardly, it may be readily removed from the bracket without being lifted bodily therefrom as is necessary in nearly all of such devices heretofore de-
25 vised. This feature is a particularly desir-
able one where the brackets are to be em-
ployed in a drug store or where a number of bottles are to be supported in tiers one
30 above the other, as the tiers may be ar-
ranged more closely together than would be possible if it were necessary to lift the bot-
tles bodily from the bracket.

In the accompanying drawing, Figure 1 is a perspective view of one of the brackets em-
35 bodied in the invention. Fig. 2 is a side elev-
ation thereof showing a bottle supported thereby, and showing the manner in which the boitle may be removed from the bracket without being lifted bodily therefrom, and
40 Fig. 3 is a front elevation of the bracket.

As shown in the drawings, the bracket in-
cludes an attaching plate 5 provided with
openings 6 through which may be passed
45 suitable securing screws 7 for attaching the
bracket upon a wall or like structure or sup-
port.

While in the drawings, the base or sup-
porting portion of the bracket and the arti-
50 cle gripping portions thereof are illustrated
as formed from two strands of wire similarly
bent, it will be understood that a single
strand may be employed if found expedient.
In any event, each strand or the end portion
55 of a single strand, should one be employed, is
secured at its extremities in or to the upper

edge of the attaching plate 5 and is bent to form a semi-annulus 8 which is in a horizontal plane with the upper edge of the said plate 5. Each of the semi-annulæ 8 is bent, intermediate its ends, to form an upstanding 60 ovate-lanceolate article gripping loop 9 which, as this portion of the device is formed of wire, is resilient, and these two loops, at opposite sides of the supporting portion of the device, are mutually inclined upwardly 65 and inwardly so that their upper or major portions will bear more firmly against the sides of the bottle or similar container being supported than will their lower or minor end portions.

At the forward end of each of the annulæ 8, the wire is bent to form loops 10 which have their inner sides preferably in contact as indicated by the numeral 11 and which project upwardly and are of substantially 70 ovate-lanceolate form except that their inner or opposed sides are slightly flattened so as to contact as heretofore stated. From the lower ends of the sides 11 of these loops the wires are bent inwardly in diverging lines as 75 indicated by the numeral 12 and to a point touching on a line drawn transversely through the center of the substantially complete annulus formed by the portions 8 be-
yond which line the end portions of the wires 80 are bent to extend in inwardly converging lines 13 the extremities being secured in or to the upper edge of the plate 5.

From the foregoing description of my in-
vention it will be seen that I have provided a 90 bottle supporting bracket in which there is provided, at each side of a supporting portion, an upstanding bottle gripping element
95 preferably in the nature of a loop, and at the front of this portion, a pair of such loops 95 which are however of less height than are the side loops and from an inspection of Fig. 2 of the drawings it will be seen that the advan-
tage of such a construction lies in the fact that in removing a bottle from the bracket, 100 it is only necessary to tilt the bottle slightly forwardly and then remove it in inclined po-
sition, previous devices, as heretofore stated, of this class, having been formed so that re-
moval of the bottles from the bracket must 105 necessarily be in a vertical direction.

A further feature of the invention resides in the specific form given to the side article gripping loops, these loops being, as stated in the foregoing description, ovate-lanceolate 110

in form with their major ends presented upwardly so that the wider portions of the loops will engage with the bottle, being supported, more firmly than will the narrow portions thereof.

5 What is claimed is:—

1. An article of the class described comprising a wire frame having a diametral supporting portion centrally broadened, and a plurality of article gripping loops arranged around the said portion, certain of said loops being of greater height than the others of said loops.
- 10 2. An article of the class described consisting of a frame having a diametral supporting portion centrally broadened and a plurality of article gripping fingers arranged around said portion, the side gripping fingers being of greater height than the others.
- 15 3. An article of the class described consisting of a wire frame having a diametral supporting portion centrally broadened, and

article gripping loops arranged at each side of the said portion, and a pair of such loops arranged at the front of said portion.

25

4. An article of the class described consisting of a wire frame having a diametral supporting portion centrally broadened, and open ovate-lanceolate article gripping fingers arranged around the said supporting portion.

30

5. A bottle bracket formed of a pair of strips each bent to inclose a segment of a circle, the bases of the segments being disposed together, and each of said strips being upbent 35 in its curved portion to form resilient article gripping loops.

35

In testimony that I claim the foregoing as my own, I have hereto affixed my signature in the presence of two witnesses.

JEROME W. BARNARD.
